CONSOLE TELEVISION CABINET

Ray C. Sandin, Northbrook, and Ralph M. La Zar, Evanston, Ill., assignors to General Electric Company, a corporation of New York

Application May 23, 1958, Serial No. 51,032

Term of patent 3½ years

(Cl. D56—4)

FIG. 1

FIG. 3

Fig. 1 is a front elevational view of a console television cabinet showing our new design;

Fig. 2 is a reduced side elevational view;

Fig. 3 is a sectional view taken on the line 3—3 of Fig. 1; and

Fig. 4 is a sectional view taken on the line 4—4 of Fig. 1.

The dominant figures of our design reside in the portions shown in full lines.

We claim:

The ornamental design for a console television cabinet, substantially as shown and described.
